Application August 5, 1942, Serial No. 453,654

1 Claim. (Cl. 170—163)

1

This invention relates to adjustable blade propellers and more particularly to regulating devices therefor such as described in our copending application Ser. No. 279,531 filed June 16, 1939, and now patent 2,307,102 and of which this application is a continuation in part.

It is a principal object of the invention to provide a self-contained regulator unit for controlling the setting of an adjustable propeller blade which is simple in construction and operation and which provides for accurate regulation and control of the pitch angle of the blade and over its speed of rotation.

It is a further object to provide a regulator assembly of this character having its own fluid pressure medium of proper predetermined characteristics as best suited for the purpose and which may be recirculated entirely apart from the engine lubricating system.

It is also an object to provide a regulator for a hydraulically adjustable propeller in which the fluid pressure system is entirely contained within mechanism which rotates with the propeller, requiring no fluid pressure connection to the engine or other stationary part.

It is also an object to provide a regulator device of this character in which a member rotatable with the blades and arranged to be acted upon by substantial centrifugal force is made to control directly the application of hydraulic pressure to secure accurate setting of the blades and regulation of the engine speeds to accurate values.

It is a further object to provide a fluid circulating system for developing the hydraulic pressure for controlling the setting of the blades which is operative to establish and thereafter only as required to maintain the desired fluid pressure conditions, thereby avoiding unnecessary working and generation of heat.

It is a still further object to provide a single regulator assembly of the character described having a predetermined quantity of fluid pressure medium, and means for indicating substantial depletion in quantity of medium.

A still further object of the invention is to provide means for indicating the sufficiency of fluid pressure operating medium in the reservoir of a self-contained regulator unit.

Other objects and advantages will be apparent from the following description, the accompanying drawing, and the appended claim.

In the drawing—

Fig. 1 is a vertical sectional view along the axis of the regulator device constructed in accordance with the present invention;

2

Fig. 2 is a transverse sectional view through the axis of the regulator at right angles to the view of Fig. 1, and substantially as indicated by the line and arrows 2—2 of Fig. 1.

Fig. 3 is a diagrammatic view showing the parts contributing to the present invention in their functional relation.

In order to provide for adjustment of the setting of the blades in a hydraulically adjustable propeller, suitable means are provided for effecting change in the pitch angle of the blades under the action of selectively applied and controlled hydraulic pressure, application Ser. No. 279,530 filed by us on June 16, 1939, now patent 2,307,101, an adjustable blade propeller is shown in which selectively and positively applied hydraulic pressure is utilized to effect both pitch-increasing and pitch-decreasing change in the blade setting, the blades being adjustable over the usual flight range, into a feathered position, and also into a negative pitch position to provide a negative thrust for purposes of landing, maneuvering, and the like. The present invention provides a regulator assembly arranged to develop and supply to the hub and blade structure separately controlled sources of hydraulic pressure for positively actuating the blade in each direction, throughout its range of adjustment to secure predetermined desired setting of the blades. This fluid pressure application is so regulated over the normal flight range as to provide for maintaining substantially constant speed of the propeller within such range as selected either manually or in accordance with instrument control, that speed being subject to change as required. And by reason of the particular construction and arrangement of the invention as hereinafter described, a highly accurate and definite speed condition is provided so that for example where a plurality of aircraft propellers are driven by separate engines, the regulating means provides for maintaining accurate conditions of setting of the blades such as to establish accurate speed control and to avoid objectionable noise and vibration from beats produced by the engines.

The invention is likewise applicable for similarly controlling a propeller which utilizes positively applied hydraulic pressure for actuating the blades only in one direction, either for pitch-increasing or pitch-decreasing purposes, the blades being returned in the opposite direction of movement under the action of centrifugal force, resilient means or the like.

The separately controlled source of hydraulic pressure for the hub and blade structure is em-

bodied in an annular housing mounted on and rotatable with the hub that encloses all of the controlling mechanism and provides a reservoir charged with a predetermined quantity of fluid pressure medium. Thus, all of the control mechanism for the most part is substantially immersed in the fluid pressure medium, which medium when the regulator is in a state of rotation, is in effect thrown against the circumferential wall of the regulator. Those parts of the control mechanism that are radially movable will then tend to float in the fluid pressure medium, or their outward movement be opposed by a force substantially equal to the mass of medium displaced by them. It is a well known fact that when any object is wholly or partially immersed in a liquid it is buoyed up by a force equal to the weight of the displaced liquid, and that the center of pressure is where the center of gravity of the submerged portion would be if it were homogeneous. As a result, the submerged and movable parts of the control mechanism are subjected to an inwardly acting buoyant force equal to the weight of the liquid displaced. Considering the control mechanism described, centrifugal force acting on the moving elements of the mechanism is resisted by the spring force plus the above described buoyant force. If the level of the fluid pressure medium falls so low that parts of the movable elements of the control mechanism become only partially immersed this buoyant force is reduced. Since centrifugal force is equal to the product of the mass moment times the square of the angular velocity, and since the force to be overcome by centrifugal force is diminished by the reduction in buoyant force, a lower speed of rotation is required to cause the control mechanism to assume its neutral position, and the controlled speed with reduced fluid level will be lower for a given control setting than when the normal fluid level is maintained. Further, the speed of rotation of the control mechanism may then be an index of the level of fluid pressure medium within which the control mechanism is immersed.

In the instant disclosure regulation of the fluid pressure application is effected by means of a radially movable valve member that responds to centrifugal force in opposition to a constantly applied spring force, thus becoming itself the governor mechanism. Designedly, the valve member along with its movable linkage, is immersed in the fluid pressure medium and is responsive to dominance of either centrifugal or spring force to effect sufficient regulation for constant speed within the range selected, regardless of the level of fluid pressure medium. However, the change of level of the medium, whether it be above or below the prescribed level, will affect the range that may be selected for control since the change in buoyancy of the immersed valve member will change the speed of rotation required to move the valve member for its control function. In substance, if the level of fluid pressure medium is above the prescribed level, then the buoyancy or flotation of the valve member is increased and a greater centrifugal force is required to press it to the equilibrium position. Conversely, if the level of the fluid pressure medium is below the prescribed level, then the buoyancy or flotation of the valve member is decreased and a lesser centrifugal force is required to press the valve member to the equilibrium position. That means that the speed setting for which regulation is to be accomplished, though selected by hand or instrument, may be lower or higher respectively than

the constant speed attained by the control mechanism. Of the two results, underspeed may be more hazardous than overspeed, since the aircraft may be less responsive to the pilot's control. It therefore is desirable to know whether or not and when the fluid pressure medium becomes materially depleted, because a low level of fluid medium results in a low top speed.

Referring to the drawing which discloses a preferred embodiment of the invention the propeller blades 10 are shown as adjustably and rotatably mounted within hub 11 the hub being provided with blade sockets corresponding to the number of blades, three being shown herein. The hub is driven from drive shaft 12 projecting outwardly from the engine casing 13, the axis of rotation of the drive shaft being shown at 14. The regulator of the present invention is indicated generally at 15, and comprises a structure located in relation to the hub so as to be rotatable therewith, avoiding the necessity for establishing fluid-tight joints for the supply of pressure operating fluid between a stationary and a rotatable part of the mechanism. Preferably as shown the regulator assembly is located immediately in front of the motor casing and adjacent to and rearwardly of propeller hub 11.

The hub 11 has a sleeve portion 16 formed integrally therewith which is provided with spline teeth 17 for engaging a similar spline upon the drive shaft 12, to provide for rotation of the hub therewith. A wedging ring 18 and locking ring 19 retain the hub in proper driving relation upon the shaft 12.

Bolted to the motor casing 13 by means of bolts 22 is a stationary plate 23 extending radially inwardly and provided with a series of bolts 24 for supporting an annular ring member 25 thereupon in stationary relation with respect to the motor casing. The ring 25 is formed integrally with a flange 26 which extends radially outwardly therefrom and has a turned-over end portion 27 which is provided with a succession of lobes around its periphery to function as a cam. Preferably the cam 27 has two high points alternating with two low points uniformly arranged around its periphery.

Seated within a recess in the sleeve portion 16 of the hub and extending radially outward therefrom is an annular member 30 which serves as a support for the valve and pump casings and associated operating mechanism. Member 30 is held in place upon the sleeve 16 by means of a locking ring 31 spaced inwardly from ring 25 with sufficient clearance to permit of rotation of ring 31 and member 30 along with hub 11, out of contact with stationary ring 25.

Member 30 extends radially outward and receives a cover plate 33 in fluid sealed relation upon its outer periphery, the cover plate having an inwardly extending web portion 34 supported upon and sealed with respect to the ring 25. The cover 33 is bolted to member 30 by means of a series of bolts 35 such that it can be removed to provide access to the interior of the regulator housing. When in position the cover thus forms a completely enclosed chamber or reservoir for the reception of the hydraulic actuating fluid, and provides a fluid-tight connection preventing escape of fluid from within the chamber for this purpose a sealing member 37 is adapted to engage the flange 34 and ring 25, being retained in sealing position by means of contractile spring 38 and cover plate 39. Likewise to prevent escape of fluid 75 from within the housing, a sealing member 40 is

provided between the inner end portion of member 30 and ring 25, being similarly retained in place by means of spring 41 and cover plate 42 held in place by bolts 43.

The pump structure and control mechanism is located within the space enclosed between the cover 33 and member 30 so that it is sealed against passage of fluid therefrom and continuously subjected to and operative in the reservoir of fluid pressure medium received therein which serves to lubricate and transfer heat therefrom. Upon rotation of the housing, fluid contained therein will move radially outwardly toward the inner wall of cover 33, which thus forms a reservoir for the fluid, the quantity thereof preferably being such that it practically fills the reservoir with only a relatively small clearance volume.

Satisfactory results are obtained with the regulator slightly more than half full of fluid, yet satisfactory operation has been obtained with as little as one pint of oil. Normal oil level requires two and one half quarts or more of fluid in the regulator. In main, calibration and ground adjustment will establish fidelity of response from the control mechanism for any predetermined level of fluid pressure medium that may be decided upon. It is therefore only necessary to have sufficient fluid pressure medium in the reservoir to serve the apparatus effecting the control.

The surface of the fluid while the apparatus is under a state of rotation with normal level is indicated at 44. It is deviation from that level, and particularly a loss of level that is of primary concern here, because operation at low oil level decreases the maximum speed at which the propeller will control, due to the loss of flotation forces on the moving governor parts. This decrease in speed may amount to about 8 to 10 percent before the oil level becomes critical, so the pilot has a regular check on oil level during each take-off or at any time in flight by moving the propeller control to a selected speed position. Noting the R. P. M. that the engine settles to for the selected propeller control will give an indication of the level of fluid pressure medium as respects the predetermined level for which the control mechanism has been adjusted and calibrated. If the engine speed obtained is coincident with the propeller setting, the indication is that the level of the medium is satisfactory, but if coincidence is not obtained and the engine speed indication is less than the propeller control setting then there is an indication that the level of the fluid pressure operating medium is low, and that it should be replenished for most efficient operation.

The inlet for picking up fluid from the reservoir comprises a funnel-shaped member 45 having a screening device 46 over the opening and extending radially outwardly toward the inner wall of the reservoir. It approaches but is spaced somewhat therefrom to avoid picking up any sludge or other deposit from the fluid, but is relatively close so that it will be assured of receiving a supply of fluid. Passing through the funnel, the fluid enters through port 47 the valve chamber 48 of a cut-off valve 49. Valve 49 stands radially of the housing so that the body thereof is subjected to outward centrifugal force in the direction to open the valve, variable with the speed of rotation. A compression spring 50 acts in the same direction as centrifugal force, to urge the valve toward open position with a constant force. The valve has a stem 51 the end of which is acted upon by fluid pressure from a pressure chamber 52 in communication with the pressure side of the pump. Pres-

sure so applied acts to urge the valve toward closed position so that upon the development of a pressure on the delivery side of the pump of the proper value, that pressure will be made effective upon the valve stem, to cause the closing of the shut-off valve and the consequent termination of the supply of fluid into the pump chamber. A safety by-pass 53 is likewise provided through the valve chamber, which is uncovered by the valve stem only after the inlet port has been substantially closed off, this by-pass providing for relief in the event of the operation of either of the pumps for the period immediately following the closing-off of the inlet ports.

15 The passage 57 leads from the control side of the shut-off valve directly into the pump valve chamber 60. Preferably the pumps and valve means therefor are duplicated, to provide more uniform conditions of operation and of developed pressure, and for this purpose a double passage 57 leads from the inlet valve chamber 48 to two pump valve chambers 60 arranged in spaced relation to each other around the periphery. The chambers 60 and pump chambers 61 are preferably formed upon the inner wall portion of member 30, and may be cast integral therewith.

20 Inasmuch as the structure of each of the pumps and associated valve means is similar to the other, only one such structure will be described in detail. Each pump comprises a cylindrical sleeve member 64 mounted fixedly in the pump chamber 61 and slidably receiving the pump piston 65 therein. The piston and cylinder are relatively elongated axially to provide a substantial bearing area and to maintain a fluid-tight seal in the absence of any packing material under the pressure conditions which are developed within the pump. It will be noted that the pump piston is mounted so that its movement is 25 not responsive to centrifugal action, the centrifugal action merely resulting in a side thrust upon the cylinder which is adequately provided for by the large bearing area. A compression spring 66 serves to move the piston outwardly of the cylinder, and the piston is guided for longitudinal reciprocating movement by means of a cross guide arm 67 of rectangular cross section which travels in a correspondingly-shaped guideway 68 formed in the chamber 61. Piston 65 is provided with a 30 recess at its outer end and roller 70 is supported therein on a bearing member 71 carried by cross arm 67. The roller 70 serves as a cam follower and has rolling bearing engagement with the face of cam 27 to cause corresponding movement of the pump piston 65.

35 As previously described, cam 27 preferably has a plurality of lobes, which are followed by the piston and the roller as the assembly rotates about the fixed cam to cause reciprocating movement of the pump piston, to a closed position under the action of the cam and then outwardly under the action of spring 66. In the arrangement shown the two pump cylinders are preferably located 90° apart so that with the double-lobed cam two complete cycles of operation of each pump in alternation are secured with each revolution of the device.

40 The pump cylinder is ported as shown at 75 and this passage leads directly into the pump valve chamber 60. The valve structure within the chamber 60 comprises an annular member 76 positioned within the chamber and forming a suction chamber 77 at the radially outer end of chamber 60 communicating directly with the suction inlet passage 57. Member 76 is provided

with a series of apertures 78 therein providing for the passage of the fluid from chamber 77 into the centrally located pump chamber 79, when the suction valve 80 is raised from its seat. Valve 80 is normally urged toward sealing position by means of compression spring 81, and is likewise mounted in such position that it is affected by centrifugal force so that it is continuously urged toward sealing position with a force corresponding to the speed plus the force exerted by spring 81.

Annular member 82 defines the chamber 79, and is also provided at its end with a series of apertures 83 leading into the discharge chamber 84 formed in valve chamber 60 toward the radially inner end thereof and defined by annular member 85. A discharge valve 86 provides for the closing off of the ports 83 and is urged toward closing position by means of spring 87 and is likewise acted upon in the same direction by centrifugal force.

The operation of the pump and valve mechanism is as follows. Upon movement of the piston 65 to expand the pump chamber under the action of spring 66, a reduced pressure is made effective within chamber 78 closing valve 86 and opening valve 80. As a result of reduced pressure fluid is introduced from the reservoir through inlet 45, past the shut-off valve 49, through passage 51, into the suction chamber 77 through the passage 78, and into the chamber 79 from which it flows directly into the pump cylinder. Upon the return stroke of the pump, the piston is cammed positively in the opposite direction, thereby subjecting the fluid within its cylinder to pressure, which causes it to flow back into chamber 79 under pressure. This causes the closing of suction valve 80, and the opening of discharge valve 86 to supply the fluid under pressure to the discharge chamber 84.

The discharge chamber 84 leads directly into a pressure conduit 90 which is preferably formed as an integral unit comprising a tube 91 of copper, steel or the like cast integrally in a housing comprising the annular member 30. As shown this conduit is arranged in circular form, providing the pressure conduit 90 extending in continuous arcuate manner around the member 30 and having communication with both the pump and valve assemblies, so that pump discharges directly thereinto.

The intake chamber and shut-off valve device is provided with a passage 95 having direct communication with conduit 90, to provide for making the fluid pressure developed by the pumps effective within the chamber 52 and upon the valve stem 51 of the shut-off valve as previously described. Thus upon operation the pumps will jointly produce a pressure within conduit 90 which is returned through passage 95 to effect actuation of the shut-off valve 49 upon the pressure reaching the value which it is desired to maintain for purposes of operation. At that point valve stem 51 moves radially inwardly against the action of spring 50 and of centrifugal force to a closed position to substantially close off the suction inlet opening 47. Thereafter, although the pump piston 65 continues to be actuated in response to rotation, it merely produces cavitation in the suction passage without drawing in fluid, and does not continue to do work and to build up an excessive and unnecessary pressure. As a result therefore unnecessary working and heating of the body of fluid with

resultant necessity for dissipation of the heat are substantially avoided.

It will be further noted that as the shut-off valve 49 is responsive to centrifugal force as well as to a constant spring pressure, the pressure required to effect closing thereof will vary with the speed of rotation. Inasmuch as the forces of friction and the like which resist a change in position of the propeller blades are subject to increase with greater speeds of rotation, it will usually be found that greater operating forces are required with higher rotative speeds; and by the construction described such greater operating pressures are automatically provided for in accordance with this invention.

In order to secure control over the position of the blades of the propeller and hence to maintain a predetermined selected speed condition of the propeller, means are provided for regulating the blade setting automatically in accordance with the speed of operation. For this purpose the member 30 is provided with an enlarged portion 100 which serves to house the regulator valve assembly. Mounted in the sleeve 101 is the regulator valve body 102 which as shown stands substantially radially so that it is itself directly subject to centrifugal force. As shown it comprises a cylindrical body portion having two spaced valve faces, 103 and 104. A passage 105 leads through sleeve 101 and into the part 100 where it communicates upon opposite sides with the two pressure conduits 90 so that the maintained fluid pressure is supplied directly to the central portion of the valve 102, between the two valve faces thereof. Being of equal projected area, the pressure between the two faces is balanced and the valve body moves freely irrespective thereof.

A passage 106 is formed through sleeve 101 in line with valve face 103, the width of the valve face being slightly greater than the width of the passage so that when properly centered the valve face will entirely close off the passage. Similarly passage 107 is related to and controlled by valve face 104. Passage 106 communicates directly with intermediate conduits 110 and passage 107 similarly communicates with inner conduits 111 which are arranged in suitable manner, preferably concentrically with conduit 90, so that the entire assembly comprising the three conduits can be constructed and cast as an integral unit.

Conduits 110 and 111 are arranged for selective communication with the blade actuating mechanism so that upon application of fluid pressure to one of said conduits, that fluid pressure is communicated to and made effective to actuate the blade adjusting mechanism of each of the blade sockets of a multi-blade propeller in such manner as to increase the blade pitch; and similarly application of fluid pressure to the other of said conduits is made effective to control the pitch of each of the blades in the opposite direction. This communication is established by means of conduits 113 and 114 extending through the rear face of each blade socket 11 and communicating respectively with outlets 113' and 114' formed in conduits 110 and 111. The corresponding outlets of each group are located at the same radial distance from axis 14, the radial distance of the two groups being different. These conduits 113 and 114 thus are in direct communication with conduits 110 and 111, respectively, and lead directly into the interior of each blade socket where suitable means are provided for effecting an increase in the pitch angle of the blade upon fluid pressure being supplied to conduits 110, 114 and for effect-

ing decrease of the pitch angle upon pressure being supplied to conduits 111, 113. In the event that it is desired to supply pressure fluid to effect actuation of the blade in only one direction and to utilize other means such as centrifugal force, or springs to cause the opposite blade movement, only a single such pressure conduit need be utilized.

Means are likewise provided for venting the fluid from one conduit during the supplying of fluid to the other and for this purpose the sleeve 101 is open at its radially inner end as shown in Figs. 1 and 3 so that fluid returning through passage 111 and entering through ports 107 can pass directly into the reservoir. At its radially outer end, the sleeve 101 is provided with a number of discharge ports 112 so that fluid returning through conduit 110 and passage 106 can likewise be freely discharged into the reservoir.

For purposes of adjustment and operating control valve body 102 is provided with a cylindrical portion 115 to which is connected a yoke member 116 upon opposite sides thereof and having a threaded socket 117 formed therein. A lever arm 118 is threadedly and adjustably engaged in the socket. Likewise extending outwardly from and fixedly attached to the sleeve 101 is a pair of guideways 120. Slidably mounted upon guideways 120 is a friction clamp 121 having an adjustable bolt 122 therein for varying the frictional engagement therewith, and formed at its outer side with a concave roller 123 adapted to engage the arm 118.

Formed integrally with arm 118 is a yoke arm 124 having hooks 125 at either end thereof for engagement with tension springs 126. These springs are relatively elongated and such as to develop substantial force, having their opposite ends fastened to a convenient point within the casing, such as the hooks 127 formed integrally upon pump chamber 61. Under the action of centrifugal force, these two springs assume a somewhat arcuate position, but because of the consequent less direct line of action of the spring force, continue to urge the yoke-shaped arm 124 and arm 118 radially inwardly and with a maintained force which is substantially constant at varying speeds or in which the variations are insignificant practically so far as the regulating action is concerned.

Roller 123 thus forms a fulcrum, lever 118 pivoting about its center, and through connection of the lever with the regulator valve body 102 acts to urge the valve body radially inward against the action of centrifugal force which acts oppositely thereon. The force with which the valve body is urged inwardly remains practically the same for any fixed setting of the roller 123 regardless of the speed of rotation as above described. However upon the shifting of roller 123 axially along arm 118, the effective lever arm of the spring force on yoke 124 is altered, a movement for example of roller 123 to the right as shown in Figs. 1 and 3 providing for the spring force being exerted with a greater lever arm. The lever arm through which this force is applied to the valve body is also increased by the same length but because it is already longer than the arm through which the spring force is applied, its length increases less in proportion and consequently there is a net increase in the inward force applied to the valve body, hence balancing a greater centrifugal force effective upon the valve body. The opposite condition occurs upon movement of the roller to the left.

In the operation of the regulator valve, with a fixed positioning of the adjustable roller 123, corresponding to a predetermined engine speed condition which it is desired to maintain, a decrease in speed will result in a reduction of centrifugal force effective upon the valve body 102 so that with the constantly acting force of the regulator springs 126, the valve body will be caused to move radially inwardly. As a result thereof, valve face 104 will uncover passage 107 and the source of pressure fluid supplied through passage 105 will be communicated through port 107 into pressure conduit 111. This supply of pressure fluid is delivered through the passages 114 which lead into the several blade sockets and to the blade adjusting mechanism contained therein, being applied in such direction as to effect a change in the setting of the blades to decrease the pitch thereof so that with a lesser angle of pitch, the speed will tend to increase and be restored to its predetermined desired condition. Simultaneously with the supply of pressure fluid into conduit 111, valve face 103 has moved inwardly to uncover the passage 106, thereby permitting fluid to exhaust from conduit 110 and from the opposite side of the actuating piston, back into the reservoir through port 112.

As the propeller increases its speed by reason of the reduced pitch angle of the blades, the added centrifugal force is effective immediately and directly upon the valve body 102 so as to cause the same to move radially outwardly to such position as to cut off further communication from the pressure passage through the passage 107, the valve moving outwardly to such point that its outward centrifugal force reaches a condition of balance with the inwardly applied spring force. If this condition corresponds with the predetermined desired speed condition as determined by the position of roller 123, the valve body occupies such position that communication with both conduits 110 and 111 is prevented. The valve body thus constitutes its own follow-up device, and because it is directly affected by centrifugal force itself, without the interposition of additional moving parts involving frictional losses, it is highly sensitive and quickly responsive to even quite small changes in speeds of operation. It will be further noted that the valve is rotated at the same speed as the propeller itself, and furthermore is positioned at a substantial radial distance from the axis of rotation so that centrifugal force effective thereon is quite substantial, and differences occurring from even small changes in speeds of rotation are highly effective to bring about the regulating action as described above. This is highly desirable in connection with multi-motored planes, in order to provide for operation of each of the propellers at such speeds as to avoid setting up objectionable vibrations, and to avoid the objectionable effects of beats from the operation of the two motors at speeds only a few R. P. M. apart. With the arrangement of the present invention a highly critical condition of regulation is provided, such that these operating characteristics in multi-motored planes are rendered unobjectionable, and such that a high degree of accuracy of regulation is provided.

Upon an increase in the speed of the propeller above that desired, the centrifugal force on the valve body exceeds the applied force of the springs and results in outward movement of the valve body 102 against the regulator spring action, caus-

ing the supply of pressure fluid into conduits 110 and 113 to effect change in the position of the blade by increasing the pitch angle thereof, with simultaneous venting of the fluid from conduit 111. This produces a reduction in the speed of operation, which is similarly responded to by the valve body to terminate the correcting application of fluid pressure, and to restore the system to its condition of stable equilibrium.

The construction of the regulator valve body as thus described likewise provides a control which is responsive to the rate of change of speed, inasmuch as a rapidly falling speed condition for instance will result in a greater degree of movement of the valve body 102 inwardly, to thereby open the port 107 more widely, to thereby supply pressure fluid at a greater rate from the source of pressure supply. The same is true of the reverse condition, the sensitive regulator body thus providing an accurate and sensitive control for such operating conditions as encountered.

The present construction provides a regulator construction which combines the features of stability through the normal working range, and at a sufficiently low idling speed, and a high degree of sensitivity particularly in the normal working range of speeds and blade angles. As will be evident, the movement of regulator valve body 102 results in a change in its radial position and hence in the centrifugal force effective thereon. To counterbalance this condition, the center of roller 123 is offset inwardly a slight distance from the line joining the point of connection to the valve body and the effective point of application of the spring force to lever 118. Hence as the valve body moves outwardly, lever arm 118 pivots about roller 123 and thereby its effective length is slightly increased, the arm in effect rolling about the center of the roller. Although actually a small valve, it produces a counterbalancing action and provides for securing the desired stability and sensitivity, the sensitivity with the construction disclosed actually increasing with increase in speed in the operating range so that a very satisfactory condition in this respect is provided.

As described above, shifting the position of the roller 123 effects a change in the force of the regulator spring effective upon the valve body, and thereby causes the regulator to seek and to become balanced at a different speed of rotation. This is desirable in order to provide for selection of the desired speed, either manually, or under the action of a control instrument. For the purpose of enabling selection of the desired speed for the operation of the regulating device, means are provided for shifting the position of roller 123 and predetermining or adjusting its position at any time during operation. As shown this means comprises a manual control member 130, pivotally mounted on a bearing member 131 carried by one of the engine bolts 22, and having suitable connection at 132 for a control wire, lever, or the like. The end of lever 130 within the cover plate 23 is formed with segmental gear teeth 133 which mesh with teeth 134 of a segmental pinion 135 carried by a rotatable shaft 136. Shaft 136 is rotatably mounted within the ring 25, and extends axially beyond the flange 26 thereof, being provided with an outwardly projecting arm 137 adjacent the inner surface of the flange 26. Arm 137 projects through a bracket 138 formed integrally with a ring 139 rotatably received upon the outer face of ring 25.

A snap ring 140 fitting within ring 25 serves to prevent axial movement of the ring 139 with respect to the ring 25 while providing for relative circular movement taking place therebetween.

5 Tongue 138 is provided with a slot 141 therein through which arm 137 projects, the slot being either straight or curved to provide for securing the proper increments of rotation of ring 139 in response to the actuation of lever 130 and the movement of the arm 137.

A cam ring 144 having a central peripheral groove 145 therein is mounted upon the outer face of ring 139, and carries a fixed pin 146 which extends radially inwardly thereof through a spirally arranged slot 147 formed in the ring 139, and into an axially arranged slot 148 formed in ring 25. As a result of this construction, and upon rotation of ring 139 about its axis, spiral slot 147 travels with respect to pin 146 and because the cam ring 144 is held against rotational movement by the engagement of pin 146 in axial slot 148, the entire pin and cam ring is caused to move axially under the guidance of pin 146 in slot 148. A plurality of such pin and slot means are provided

15 around the periphery of the ring in order to develop a balanced driving force and to avoid binding of the ring, any tendency toward binding being further reduced as a result of the full lubrication of the parts exposed within the reservoir, 20 and by reason of the relative rotational movement simultaneously taking place between the cam ring and ring 139. Accordingly movement of lever 130 is made effective to produce a predetermined axial shifting in the position of cam 25 ring 144, the particular relationship depending upon the contour of the cooperating arm and slot 141 as previously described.

In order to transmit this movement of the cam block into a corresponding movement of the 40 roller 123, diametrically opposite cam followers 150 carried by levers 151 are engaged within the groove 145. Levers 151 are pivotally mounted upon fulcrum arms 152 carried by the brackets 128, and are adapted to be rocked thereon in response to movement of cam ring 144. The levers at their opposite ends are preferably connected together by a cross strut 153 and have outwardly extending parts 154 each formed with a clevis engaging lugs 155 formed upon the bracket 156 to which the friction clamp 121 is attached. As shown, movement of the cam ring 144 axially results in pivoting of lever arms 151 and the consequent movement of the friction block 121 axially over the supporting rod 120. Thus in response to adjustment of the lever 130 either manually or by instrument control, the fulcrum roller 123 is made to change its position, causing a change in the force with which the regulator spring acts upon the regulator valve body, to in turn result 50 in regulating the speed of operation of the propeller blades to a value corresponding to the selected speed desired, equilibrium being established at the desired new speed condition in the manner as previously described.

65 For example when the control lever 130 is actuated to such position as to cause the fulcrum roller 123 to approach the point of application of the regulator springs, the moment of application of that spring force is reduced, thus causing the 70 valve body to move outwardly and to effect the application of fluid pressure in such direction as to effect an increase in the setting of the blade angle. The speed thus slows down and the centrifugal force effective upon the valve body to balance the regulator spring force is likewise re-

duced. This is provided for automatically by the regulator action as above described, the blade angle being progressively increased with a correspondingly reduced speed of rotation of the blades the closer the fulcrum point of the roller 123 approaches the point of application of the regulator springs.

On the other hand, as the fulcrum roller 123 moves to the right as shown in Figs. 1 and 3 a greater force is applied from the regulator spring to the valve body causing it to move inwardly to such position as to effect the application of pressure to decrease the pitch of the blade. The propeller then speeds up producing a greater centrifugal force upon the valve body so that the regulator provides for reducing the setting of the blade angle as the fulcrum roller is progressively moved further in this direction.

All of the foregoing is in contemplation of the fact that the level of the hydraulic fluid is at the predetermined level for which the control mechanism is calibrated and adjusted. Whether the predetermined level be that at which the reservoir is nearly full, about half full or but partially filled, the control mechanism when correspondingly calibrated and adjusted will function quickly and within close limits of the designed setting. That fidelity of control is due to the fact that the valve body stands within and displaces fluid contained in the reservoir, with the fluid exerting a pressure effect upon the valve body that tends to oppose the action of centrifugal force thereupon. As the level of the fluid is reduced by depletion, that opposing force is lessened with the result that the valve body will move outwardly and reach equilibrium at a slower actual speed of rotation than that for which the control 130 is set, thereby indicating to the pilot the loss of or reduction in the quantity of fluid in the reservoir.

To facilitate determination of fluid deficiency the manual for actuating the lever 130 of the propeller control is closely associated with the engine speed indicating device, such as a tachometer, all of which is schematically shown in Fig. 3 of the drawings, where an articulated motion translating means, such as the links 160, 161 and rocker 162 joins the lever 130 at 132 and ends at a lug 163 of a rotatable or oscillatable ring 164. The ring 164 is disposed for oscillation about the housing of a tachometer 165 through the agency of a handle 166. As is customary, the tachometer 165 is geared to the drive shaft 12 by the gear elements 167 and 168 and a shaft element 169 which operates to move an arrow or pointer 170 over a scale 171 in accordance with the speed of the shaft 12. The graduations 172 of the scale operate as an index of the engine R. P. M. and also function as an indication for the setting of the propeller control.

As one example, for take-off the propeller control is moved to the corresponding indication, under which conditions the propeller should be at the full forward position or high speed setting, which for purposes of illustration may be assumed to be 2800 R. P. M. as indicated in Fig. 3. The engine will accordingly have been adjusted as respects throttle and the like, thereby making use of full military power which should result in the engine settling to a top speed of 2800 R. P. M. While "take-off" has been mentioned as a specific example under which notation or test of fluid level may be made, it is a fact that the test may be made at any time while the aircraft engine is self-operative. Thus, if the engine settling speed is the same, as that indicated by the propeller

control setting, that is, if the tachometer arrow 170 becomes coincident with the arrow 174 of the propeller control, then the indication is that the liquid level of the reservoir is as designed. However, the tachometer arrow 170 may assume a position at engine settle speed that is out of coincidence with the propeller control arrow 174, which indicates that the level of the liquid in the reservoir is other than that intended. If the tachometer arrow fails to reach the position of coincidence as indicated by full lines in Fig. 3, and stops short of that position, such as at the dotted line position indicated by 170a, then there is an indication that the liquid level of the reservoir is low and that replenishment thereof should be made reasonably soon or at the earliest convenience. A further check on the foregoing can be made at any time while in level flight. An opportune time to do so is while flying under military power.

The invention thus provides a highly accurate and stable though sensitive regulator device for maintaining control over the blade positionings and over the speed of operation. In use, a desired speed condition is maintained with such accuracy that objectionable beats from multi engines are avoided. Being self-contained the system is less subject to failure and the fluid itself is that best adapted for the purpose. The adjustable control provides for securing regulation of the operative condition at a selected range, and serves in the normal operative range, as a proving device for testing the condition or sufficiency of the fluid medium.

While the form of apparatus herein described constitutes a preferred embodiment of the invention, it is to be understood that the invention is not limited to this precise form of apparatus, and that changes may be made therein without departing from the scope of the invention which is defined in the appended claim.

What is claimed is:

In a hydraulically controlled constant speed variable pitch propeller having a reservoir rotatable therewith and enclosing a quantity of fluid pressure medium, with pitch control apparatus including a governor valve immersed in the medium and responding to the combined effects of centrifugal force and flotation of the valve in the medium for controlling the blade pitch to effect propeller operation consistent with a predetermined selected speed, the combination of means for detecting a variation in flotation of the valve in the fluid pressure medium, and compensating for the influence of the varied flotation upon the response of the valve to effect selected speed operation, said means including a tachometer with scale and needle for indicating the actual propeller speed, a manually operated member for actuating the propeller pitch control to effect a blade angle suitable for the selected speed indicated by the tachometer and including a part rotatable about the tachometer scale and having an index cooperable with the scale for translating blade pitch to speed indication, the coincidence of both needle and index with the same selected speed point on the tachometer scale indicating a prescribed quantity of fluid medium in the reservoir and hence a prescribed flotation force applied to the valve, and non-coincidence of both the needle and index with a selected point on the scale of the tachometer indicating other than a prescribed quantity of fluid medium in the reservoir and hence a variation from the prescribed flotation force applied to the valve and

thereby a deviation from the selected speed, and means including the manually operated member with linkage to the propeller control for adjusting the propeller pitch until the needle for propeller speed coincides with the selected point on the scale of the tachometer, thereby altering the actual blade setting for compensation of the variation in flotation force applied to the valve and accomplishing a propeller speed of operation consistent with the predetermined selected speed.
